UNITED STATES PATENT OFFICE

124,126

DESIGN FOR A TOILET MIRROR

Walter J. Bohn, Toledo, Ohio, assignor to The Acme Specialty Manufacturing Company, Toledo, Ohio, a corporation of Ohio

Application July 22, 1940, Serial No. 93,831

Term of patent 7 years

To all whom it may concern:

Be it known that I, Walter J. Bohn, a citizen of the United States and resident of Toledo, in the county of Lucas and State of Ohio, have invented a new, original, and ornamental Design for a Toilet Mirror, of which the following is a specification, reference being had to the accompanying drawing, forming a part thereof.

Fig. 1 is a front perspective view of a toilet mirror showing my new design, and Figs. 2 and 3 are rear and end elevations thereof, respectively.

The front panel member shown in Fig. 1 constitutes a light diffusing glass disposed over a light transmitting source.

The dominant features of my design reside in the portions shown in full lines.

I claim:

The ornamental design for a toilet mirror, substantially as shown and described.

WALTER J. BOHN.
